UNITED STATES PATENT OFFICE.

ADDIE E. CHERRY, OF BELLWOOD, PENNSYLVANIA.

CHURN.

No. 906,198.

Specification of Letters Patent.

Patented Dec. 8, 1908.

Application filed October 30, 1907. Serial No. 399,840.

To all whom it may concern:

Be it known that I, ADDIE E. CHERRY, a citizen of the United States, residing at Bellwood, in the county of Blair, State of Pennsylvania, have invented certain new and useful Improvements in Churns; and I do hereby declare the following to be a full, clear, and exact description of the invention, such as will enable others skilled in the art to 10 which it appertains to make and use the same.

The present invention has reference to churns, and it aims, generally, to provide an exceedingly simple, inexpensive, and ef- 15 fective device of that nature.

More particularly, however, it is the object of the invention to provide a churn in which a thorough agitation of the contents of the cream can is effected by the use of 20 two separate sets of dashers, one set being secured to the dasher shaft so as to rotate therewith, while the other set is carried by the cover of the can, which latter is rotated in a direction opposite that of the dasher 25 shaft, the connection between the second set of dashers and the can cover being such that the dashers may readily be removed therefrom for cleaning purposes.

The invention further resides in the pro- 30 vision of a churn which may be converted into and utilized as an ice cream freezer by merely detaching the second or relatively stationary set of dashers.

A still further improvement resides in the 35 formation of an air passage in the dasher shaft, which passage extends below the level of the can lid and communicates at such point with the interior of the can to permit the entry of air thereinto.

With the above and other ends in view, the invention consists in the construction, combination, and arrangement of parts, all as hereinafter fully described, specifically claimed, and illustrated in the accompany- 40 ing drawings, in which like parts are designated by corresponding reference numerals in the several views.

Of the said drawings:—Figure 1 is a vertical section through a churn constructed in accordance with the present invention. Fig. 2 is a transverse section in the line 2—2 thereof. Fig. 3 is a bottom plan view of the can cover. Fig. 4 is an enlarged detail view of the set of dashers carried by the 50 cover. Fig. 5 is a detail view of the extensible handle carried by the drive shaft.

Fig. 6 is a vertical section through the device utilized as an ice cream freezer.

Referring more particularly to the drawings, 7 designates the outer receptacle or 60 tub whose bottom is provided with a step bearing 8 in which a depending projection 9 formed on the bottom of the cream can 10 is adapted to fit, this projection being socketed for the reception of the lower end of the 65 dasher shaft 11.

The tub carries at its top a strap 12 of the usual type, which strap is provided with an integral cap portion 13 located intermediate the ends thereof. The shaft is squared at 70 its upper end and carries at such point a beveled pinion 14 provided with a hub 15 which, with the shaft, extends through a central opening in the cap 13, the pinion being retained in place upon the shaft by 75 means of a set screw 16 which extends through an opening in its hub and impinges against the shaft. The strap above referred to, whose body portion is disposed slightly above the top of the tub serves also as a 80 support for the drive shaft 17 upon the inner end of which is mounted a beveled pinion 18 which meshes with the pinion 14 and with an oppositely facing pinion 19 formed upon the cover 33 of the cream can, the last men- 85 tioned pinion being provided with an axial opening through which the dasher shaft extends into the interior of the can, rotation of the drive shaft thus effecting a rotation in opposite directions of the dasher shaft and 90 can, the cover of which is provided with a series of depending pins 20 which engage correspondingly located hooks 21 formed on the can, the can and its cover being held together by this means.

The shaft 11 carries a main dasher in the form of an open rectangular frame comprising upper and lower cross pieces 22 which extend through openings formed through the dasher shaft, and have their correspond- 100 ing ends secured to vertical blades 23 which extend a slight distance above and below the cross-pieces 22. In addition, the dasher shaft carries a series of horizontal plates which project laterally therefrom and are 105 arranged in staggered relation, one above the other.

The second set of dashers which are rotated in a direction opposite to that of the first-mentioned set, comprises a series of 110 three or more vertical plates 25 connected together at their upper and lower ends by

hoops 26, the plates being slit at such points to permit the engagement of the hoops therewith. These plates are connected with the can cover by means of a series of pairs of 5 depending fingers 34 which are formed on the under face thereof and engage with the upper edges of the plates, each plate being fitted between a pair of fingers. It is therefore apparent that when the can and its 10 cover are rotated, the attachment of the plates to the cover causes the same to rotate therewith. Each plate is preferably provided with a series of openings through which the contents of the can pass during 15 the rotation of the latter. The arrangement of the several plates is such that they extend inwards towards the dasher shaft, their upper and lower edges being in contact with the bottom and cover of the can, and their 20 outer vertical edges with the vertical wall of the can, to which they are set at an angle. In order to admit air into the interior of the can during its rotation, the dasher shaft is provided with a longitudinal bore 27 25 which extends from the upper end of the shaft to a point below the plane of the upper edges of the blades 23, at which point the bore communicates with an opening 28 formed transversely through the shaft. The 30 outer end of the drive shaft 17 carries a handle 29 by means of which its rotation is effected.

From the foregoing it will be apparent that upon rotation of the drive shaft, the 35 can and dasher shaft will rotate in opposite directions, the provision of the two separate sets of dashers effecting a thorough agitation of the contents of the can, this agitation being enhanced by the formation of the openings 40 in the plates 25 and by the entry of air into the interior of the can through the air passages 27 and 28.

The device above described can be readily converted into and utilized as an ice cream 45 freezer by merely detaching the second or cover-carried series of dashers from the cover. It is advisable, however, to make use of a smaller can in order to dispose the outer edges of the blades 23 sufficiently close to the 50 wall of the can. In either instance a space exists between the inner wall of the tub and the outer wall of the can, which space is

adapted to be filled with either hot or cold water when the device is utilized as a churn, and with ice when used for freezing purposes. 55

The handle 29 by means of which the drive shaft is rotated is preferably formed in two sections so as to afford a greater or less leverage, one of said sections being provided with a longitudinal slot through which projects a pin 31 formed on the other section, the pin carrying a jam nut 32 at its outer end. 60

The plates 25 are preferably formed of 65 sheet metal, while the hoops 26 which are engaged therewith are formed by metal straps whose opposite ends are connected in any desired manner. While three plates are shown in the present instance, it is understood that there is to be no limitation to 70 this number.

What is claimed is:—

In a mixing machine, the combination of 75 a tub; a rotatable receptacle disposed within the tub; a removable cover for the receptacle provided upon its inner face with a series of pairs of fingers; means for locking the cover upon the receptacle; a gear provided upon the outer face of the cover and 80 formed with an axial opening; a dasher shaft extending through said opening and formed with a longitudinal air passage extending below the plane of the cover and opening through the upper end of the shaft, 85 said passage communicating at its lower end with a second air passage formed transversely through the shaft; a series of dashers carried by said shaft; a series of dasher plates carried by the cover and having their upper 90 ends engaged with said fingers; upper and lower hoops engaged with said plates for joining the same together; a gear carried by the dasher shaft; a drive shaft; and a gear carried by the drive shaft and engaged with 95 the gears carried by the cover and dasher shaft, for rotating the latter and the cover in opposite directions.

In testimony whereof, I affix my signature, in presence of two witnesses.

ADDIE E. CHERRY.
